(57) **CLAIM**

The ornamental design for a sport game, as shown and described.

DESCRIPTION

FIG. 1 is a front-perspective view of a sport game showing the claimed design.

FIG. 2 is a back-perspective view of the sport game shown in FIG. 1.

FIG. 3 is a front view of the sport game shown in FIG. 1. FIG. 4 is a back view of the sport game shown in FIG. 1. FIG. 5 is a right-side view of the sport game shown in FIG. 1.

FIG. 6 is a left-side view of the sport game shown in FIG. 1.

FIG. 7 is a top view of the sport game shown in FIG. 1; and, FIG. 8 is a bottom view of the sport game shown in FIG. 1. The dashed lines in the figures show portions of the sport game that form no part of the claimed design.

1 Claim, 8 Drawing Sheets
